CONTAINER WITH OPENER

William F. Punte, Passaic, N. J., assignor to Continental Can Company, Inc., New York, N. Y., a corporation of New York

Application June 11, 1942, Serial No. 446,668

5 Claims. (Cl. 220—43)

The invention relates generally to container structures, and more particularly to container structures of the type wherein the closure of the container is effected through the medium of a plug frictionally mounted in the container mouth or opening, and it seeks to provide a novel container structure wherein is included a plug lifting lever of novel form which is so mounted as to be permanently retained on the container and yet be free to be moved about the circumference thereof so that its lifting force can be applied under any selected portion of the plug.

Container structures of the character stated including attached plug lifter levers have been known heretofore, but many of these structures have been found impractical because of the complicated construction and manner of mounting of the levers, because of the fixed attachment of the levers at some one position on the plug or container top circumference, or ineffectiveness in operation because of faulty construction and mounting. It is the purpose of the present invention to provide a structure which is simple in form and can be inexpensively produced, and which is devoid of all of the above mentioned disadvantages.

An object of the invention is to provide a novel container structure of the character stated including a simple form of plug lifting lever which is freely movable about the seam bead at the top of the container and yet is permanently attached thereto so that the container may be opened and resealed repeatedly with the lever always available for opening purposes at any selected position about the circumference of the container.

Another object of the invention is to provide in a container structure of the character stated a lifter lever including a flat body disposed to lie flatly against the exterior of the container with an upper end portion directly beneath the seam bead at the top of the container and having an offset extension loosely turned over said bead and terminating in a wide flat lever portion beneath the plug flange so that the lever can be slid about to any selected position on said bead and then swung laterally, or in the general plane of said flat body, and about the fulcrum of one edge of said wide lever portion to cause the wide lever portion to lift the plug.

Another object of the invention is to provide a lifter lever of the nature stated in which the offset is angularly disposed with relation to the main lever body and the seam bead so as to provide a triangular clearance which facilitates

swinging of the lever to the plug lifting position without disturbing permanent loose attachment of the lever to said bead.

With the above and other objects in view that will hereinafter appear, the nature of the invention will be more fully understood by following the detailed description, the appended claims and the several views illustrated in the accompanying drawing.

10 In the drawing:

Figure 1 is a side elevation and part vertical cross section of a container embodying the invention.

Figure 2 is an enlarged cross section taken at the position of the plug lifting lever.

Figure 3 is an enlarged face view illustrating the lever in its normal position.

Figure 4 is a view similar to Figure 3 illustrating the lever swung to its plug lifting position.

20 In the example of embodiment of the invention herein illustrated, the container comprises a body 5 having the usual bottom closure 6 affixed thereto. A top ring 7 is secured to the upper end of the body, as by a double rolled seam 8 which projects outwardly from the body in the usual manner as is clearly illustrated in Figure 2. The top ring terminates inwardly in a downwardly turned flange 9 defining an opening 10 adapted to frictionally receive the closure plug generally designated 11.

25 The closure plug includes an outwardly directed flange 12 preferably folded under in the form of a reinforcing bead 13, and the generally vertical wall of the plug preferably is offset as at 14 so that the depth of insertion of the plug in the opening 9 will be definitely limited so as to provide a space beneath the plug bead 13 and above the top surface of the top ring 7.

30 Another object of the invention is to provide in this illustration a lifter lever including a flat body portion 15 shaped from a single piece of flat strap metal including a flat body portion 16 adapted to lie flat against the outer surface of the container body 5 in the manner clearly illustrated in Figures 2 and 3 of the drawing. At its lower end the body 16 includes an outwardly bent finger piece 17, and at its upper end and at one side thereof the main body 16 terminates in an abutment shoulder 18 of limited width and disposed directly beneath the outwardly directed seam bead 8 in the manner clearly illustrated in Figures 2 and 3. To one side of the abutment shoulder 18 the lever is provided with an angularly disposed offset 19 forming a triangular clearance 20 beneath the seam bead 8 at that

side of the abutment shoulder 18, said offset serving to dispose the body extension 21 against the outer surface of the seam bead 8. At its upper extremity the extension 21 is bent loosely over the seam bead 8 as at 22, thus causing the upper end of the lever to loosely embrace and conform to the shape of the seam bead. Thus the lever can be slid circumferentially about the seam bead and yet cannot be removed therefrom because of the engagement of the abutment shoulder 18 beneath the bead.

The lever extends downwardly inwardly of the seam bead, as at 24, and is then turned inwardly to present a wide lifter extremity 25 in the space intervening the plug bead 13 and the upper surface of the top ring 7.

The clearance 20 provided by the angular offsetting of the lever extension 21 as at 19 makes it possible to swing the flat lever body 16 edgewise in the manner illustrated in Figure 4. Such swinging of the lever will tilt the wide lifter flange 25 beneath the plug flange 13 and cause the plug to be lifted in the manner illustrated in Figure 4. Since the lever can be freely slid about the circumference of the seam bead 8 in the manner hereinbefore described, this lifting function can be performed at any place about the circumference of the container.

While it is preferred that the offset 19 be angularly disposed in the particular manner illustrated in Figure 3 so that it will generally parallel the bead when the lever is swung to its lifting position as illustrated in Figure 4, it is to be understood that the invention is not limited to the particular angular relation shown, but rather comprehends the provision of any form of clearance so related to the abutment shoulder 18 as to permit the edgewise swinging of the lever necessary to cause the lever portion 25 to properly lift the plug.

It is, of course, to be understood that the details of structure and the arrangement of parts may be variously changed and modified without departing from the spirit and scope of the invention.

I claim:

1. A container including a body, a top ring having a closure plug receiving opening therein, a seam bead projecting outwardly from the top extremity of the body and attaching the ring to the body, a closure plug frictionally engaging in said opening and having an outwardly extending flange overlying the ring in spaced relation, and a plug lifting lever including a wide flat portion underlying the plug flange, a portion loosely extending over the seam bead, a main body depending flatwise in close proximity to the outer surface of the container body beneath the seam bead, and a shoulder abutment portion engageable under the seam bead in position for cooperating with the portion extending over the seam bead in preventing removal of the lever while permitting movement thereof to selected positions about the circumference of the container, said shoulder abutment portion being offset with respect to said portion loosely extending over the bead and terminating at a point in substantially vertical alignment with an edge thereof, whereby said main body is swingable edgewise to tilt said wide flat portion and effect a lifting of the plug.

2. A container including a body, a top ring having a closure plug receiving opening therein, a seam bead projecting outwardly from the top extremity of the body and attaching the ring to the body, a closure plug frictionally engaging in

said opening and having an outwardly extending flange overlying the ring in spaced relation, and a plug lifting lever formed from a single piece of flat strap metal to include a wide flat portion underlying the plug flange, a portion loosely extending over the seam bead, a main body depending flatwise in close proximity to the outer surface of the container body beneath the seam bead, and a shoulder abutment portion engageable under the seam bead in position for cooperating with the portion extending over the seam bead in preventing removal of the lever while permitting movement thereof to selected positions about the circumference of the container, said shoulder abutment portion being offset with respect to said portion loosely extending over the bead and terminating at a point in substantially vertical alignment with an edge thereof, whereby said main body is swingable edgewise to tilt said wide flat portion and effect a lifting of the plug.

3. A container including a body, a top ring having a closure plug receiving opening therein, a seam bead projecting outwardly from the top extremity of the body and attaching the ring to the body, a closure plug frictionally engaging in said opening and having an outwardly extending flange overlying the ring in spaced relation, and a plug lifting lever formed from a single piece of flat strap metal to include a flat main body portion lying flatwise against the container body beneath the seam bead and having a limited width abutment shoulder at one side thereof and engaging under said bead, an offset portion at the other side thereof extending upwardly adjacent to and loosely passing over the bead and providing a clearance beneath the bead at the side of the abutment shoulder to permit edgewise swinging of the body portion without displacing the abutment shoulder from under the bead, and a wide flat portion underlying the plug flange and engageable therewith when the body portion is swung edgewise for lifting said plug.

4. A container including a body, a top ring having a closure plug receiving opening therein, a seam bead projecting outwardly from the top extremity of the body and attaching the ring to the body, a closure plug frictionally engaging in said opening and having an outwardly extending flange overlying the ring in spaced relation, and a plug lifting lever formed from a single piece of flat strap metal to include a flat main body portion lying flatwise against the container body beneath the seam bead and having a limited width abutment shoulder at one side thereof and engaging under said bead, an angularly disposed offset portion at the other side thereof extending upwardly adjacent to and loosely passing over the bead and providing a triangularly shaped clearance beneath the bead at that side of the abutment shoulder to permit edgewise swinging of the body portion without displacing the abutment shoulder from under the bead, and a wide flat portion underlying the plug flange and engageable therewith when the body portion is swung edgewise for lifting said plug.

5. A container including a body, a top ring having a closure plug receiving opening therein, a seam bead projecting outwardly from the top extremity of the body and attaching the ring to the body, a closure plug frictionally engaging in said opening and having an outwardly extending flange overlying the ring in spaced relation, and a plug lifting lever including a wide flat flange underlying the plug flange, a portion loosely extending over the seam bead, and a main body

depending flatwise in close proximity to the outer surface of the container body beneath the seam bead, said main body having a portion underlying the seam bead in opposition to the portion extending over the seam bead and including an abutment shoulder in position for cooperating with said portion extending over the seam bead in preventing removal of the lever while permit-

ting the movement thereof to selected positions about the circumference of the container, one said portion having a part bearing angular relation to the seam bead so as to provide a clearance permitting sidewise swinging of the lever main body effective to cause the wide flat flange to lift the plug.
